PISTON

Russell G. Berry, Maplewood, Mo., assignor to
 Carter Carburetor Corporation, St. Louis, Mo.,
 a corporation of Delaware

Application August 4, 1938, Serial No. 222,979

4 Claims. (Cl. 309—7)

This invention relates to pistons particularly of the type used in pumps.

Pump pistons, such as those used in automotive carburetors for providing an extra accelerating charge, are frequently provided with cup-shaped sealing leathers having disc-shaped end walls and cylindrical skirt portions intersecting in a corner of small radius. The leather skirt is yieldingly urged against the pump cylinder wall to form a piston seal and during reciprocation of the piston, particularly, in the direction towards which the concave face of the piston leather faces, a slight crimping occurs at the corner which, after repeated operation, weakens the leather and frequently results in cracks. The leather cup may be formed in a circular die which process results in weakened corner structure, further aggravating the difficulty.

An object of the present invention is to provide a pump sealing leather which is substantially more resistant to failure due to crimping, as described above, than pump leathers heretofore known.

A more detailed object is to provide a pump sealing leather without a relatively sharp corner at the intersection of the skirt and end wall portions thereof. Still another object is to provide a pump sealing leather adapted to be formed in a die without weakening of restricted portions thereof, such as occurs in die-formed cup-shaped leathers.

These objects and other more detailed objects hereafter appearing are attained substantially by the structure illustrated in the accompanying drawing in which:

Fig. 1 is a side view and section of an automotive carburetor including an accelerating pump embodying the invention.

Fig. 2 is a perspective view illustrating the pump piston, a part being broken away and sectioned for clearer illustration of the underlying structure.

Fig. 3 is a section taken approximately on line 3—3 of Fig. 2 and

Fig. 4 is a side view showing an old form of pump piston, a part being broken away and sectioned for clearer illustration.

The carburetor shown in Fig. 1 includes a constant level chamber 5 and downdraft mixture barrel 6 flanged at the lower end as at 7 for attachment to the intake manifold (not shown) of an associated internal combustion engine. The fuel level in chamber 5 is maintained substantially constant by inlet needle valve 8 controlled by float 9. Fuel reaches the mixture bar-

rel from chamber 5 through a calibrated orifice member 10 controlled by metering rod 11 carried by lever 12 pivoted above the constant level chamber. An extra supply of fuel for accelerating purposes is supplied by a pump including cylinder 13 inside the constant level chamber and a piston, generally indicated at 14, and operated from the throttle valve through the intermediary of lever 12, link 15, and crank 16 secured to the throttle valve shaft 17.

The pump piston, more clearly shown in Figs. 2 and 3, comprises a rigid body or inner clamping portion including a dome-shaped upper part 18 and a cylindrical lower part 19 forming a dome for trapping cushioning air. Between parts 18 and 19 is a groove 20 in which is received an annular coiled spring 21. Piston rod 22 is rigid with part 18 and projects from the center thereof.

The pump sealing or packing washer, preferably of leather, includes a dome-shaped or hemispherical transverse or end wall 23 seated against the transverse surface of part 18 around rod 22 and a cylindrical section 24 forming a skirt for initially engaging the pump cylinder wall and yieldingly urged thereagainst by spring 21. A curved washer 25 is seated against shoulder 26 on piston rod 22 and has an inner surface shaped as a spherical sector forming a reinforcing backing for the pump leather. Washer 25 is substantially smaller in diameter than the cylinder 13 which allows a substantial portion of the sealing leather to flex as the direction of motion is changed. Rod 22 is threaded at its lower end and provided with a nut 27 and washer 28 for maintaining the assembly.

Fig. 4 shows a pump piston having a chamber sealing leather of known shape including cylindrical skirt 32 and disc-shaped end wall 29. A spring 30 urges the skirt outwardly. The skirt and end wall meet in a relatively sharp corner 31. By comparison with Fig. 4, it will be seen that the novel leather sealing member in Fig. 2 has no sharp corner as at 31 in Fig. 4 which causes stress concentration during the pressure stroke. In addition to eliminating the sharp corner which tends to weaken after repeated reciprocations, due to crimping, the dome-shaped leather in Fig. 2 is shaped so that strains produced therein during formation in a die are equally distributed over the body of the leather.

The novel pump leather may be formed hemispherical or dome-shaped in its entirety, or provided with a short, cylindrical section at its lower open end for rubbing against the pump cylinder wall. Use of the piston in an ac-

celerating pump is not essential. The exclusive use of all modifications as come within the scope of the appended claims is contemplated.

I claim:

1. For use in a pump of the class described having a pump cylinder, a piston having a substantial portion of its length extending from its head end of cylindrical form and adapted to slidably fit the pump cylinder, a substantially reduced cylindrical portion extending therefrom toward its opposite end and having its opposite end formed hemispherical, the radius of said hemisphere being substantially less than one-half the diameter of said head end cylindrical portion.

2. For use in a pump of the class described having a pump cylinder, a one-piece piston having a substantial portion of its length extending from its head end of cylindrical form and adapted to slidably fit the pump cylinder and having its opposite end of hemispherical form and of substantially smaller diameter than said cylindrical portion and having an annular recess in-

termidiate said cylindrical portion and said hemispherical end.

3. A piston as described in claim 2 which is further characterized by a longitudinal central bore therethrough and a counterbore at the head end thereof.

4. For use in a pump of the class described having a pump cylinder, a piston formed of a single piece of material having a substantial portion of its length extending from its head end of cylindrical form and adapted to slidably fit the pump cylinder, and having its opposite end of hemispherical form and of substantially smaller diameter than said cylindrical portion and

10 having an annular recess intermediate said cylindrical portion and said hemispherical end, and a cup-shaped resilient packing member having a hemispherical closed end adapted to fit over the hemispherical end of said piston and having a skirt long enough to extend beyond said annular recess.

RUSSELL G. BERRY.
